DISPLAY CARTON

Walter H. Hermsdorf, Chicago, Ill., assignor to
 Chain Store Products Corporation, Chicago,
 Ill., a corporation of Delaware

Application May 6, 1933. Serial No. 669,645

3 Claims. (Cl. 206—47)

This invention relates to improvements in cartons and refers specifically to a display carton adapted to simultaneously retain and attractively display articles having different physical characteristics or shapes.

The utility, objects and advantages of my invention will be apparent from the accompanying drawing and following detail description.

In the drawing, Fig. 1 is a front elevational view of the embodiment of my invention in assembled position.

Fig. 2 is an end elevational view of the device shown in Fig. 1.

Fig. 3 is an enlarged elevational view of a pin adapted to be retained and displayed in conjunction with the carton.

Fig. 4 is a development of the container holding portion of the carton.

Fig. 5 is a development of the pin holding portion thereof.

Fig. 6 is a fragmentary sectional view of the lower portion of the carton.

Referring in detail to the drawing, 1 indicates a carton for holding a bottle 2 or other container. 25 Carton 1 may be constructed of cardboard or the like and may comprise face panels 3, ends 4 and bottom 5 folded along lines 6 and 7, respectively. A fold line 6 may divide one of the face panels 3 from tongue 8 which, when the carton is assembled, may be adhesively or otherwise united to the opposite end 4. Each of the ends 4 may terminate at its bottom in notched tongues 9 which are adapted to engage with each other when the carton is assembled. A fold line 7 separates bottom 5 from tab 10, said bottom being adapted to embrace the interlocked tongues 9, tab 10 being tucked in adjacent panel 3.

The carton 1, thus formed, is adapted to hold a bottle 2 or other container the upper portion 40 of which extends above the top of the carton in an attractive manner.

In assembling the carton, after tongues 9 have been locked together and previous to the insertion of tab 10, a strip 11 may be disposed between said tongues and bottom 5. Strip 11 may comprise a bottom portion 12, two side members 13 and tabs 14. The bottom portion 12 may be interposed between tongues 9 and bottom 5 and tabs 14 may be inserted within the carton adjacent the upper portions of ends 4, said tabs being normally maintained in position by means of container 2 carried by the carton. The construction is such that, the length of the side members 13 between fold lines 15 and 16 is greater than the length of the ends 4 and hence when strip

11 is positioned, as described said side members are bowed outwardly, as shown best in Fig. 1. This provision tends to further increase the attractiveness of the carton, especially when the container carried by the carton has an arcuate 60 shaped protruding portion, as the shoulders upon bottle 2.

As an added feature, incisions 17 may be provided adjacent each end of side members 13 through which hair fasteners 18 may be inserted. 65 The legs of fasteners 18 may be arcuate in shape, as shown in Fig. 3, and the length of side members 13 may be so correlated with respect to the length of ends 4 that the curvature of said side members may conform to the arc or curvature 70 of the legs of the fastener. Fasteners 18, in addition to being carried by said members 13, being arcuate in shape, tend to reinforce or maintain said side members in curved position.

It is to be understood, of course, that any type 75 container may be carried by carton 1 and that any type pin, clasp or fastener may be carried by side members 13 and that the articles carried by the side members may or may not bear some relationship to the material carried in the container. In one embodiment, for instance, the material carried in container 2 may comprise a hair waving solution whereas fasteners 18 may be used as hair wavers or wave set pins.

I claim as my invention:

1. In combination, a carton for holding a container having side walls and a bottom, the upper portion of said container being adapted to protrude from the carton, a bow strip carried adjacent a wall of the carton the upper portion of 80 which is maintained in position between the container and the carton, an arcuate shaped pin carried by said bowed strip serving to maintain said strip in bowed position.

2. In combination, a display carton comprising 85 side walls and a bottom, said display carton being adapted to hold a container of substantially the same cross section as that of the carton, a strip forming a portion of the bottom and disposed in arcuate form adjacent opposite sides of the carton, the ends of said strip being positioned in the top of the carton between the carton walls and the container, the arcuate portions of said strip being adapted to hold arcuate shaped pins inserted in incisions provided in said strip.

3. In combination, a display carton for holding a container, comprising side and end walls, a bottom foldably connected to one of said side walls and having a tab adapted to be disposed adjacent the opposite side wall, locking tongues 100 105 110

forming foldable continuations of said ends and adapted to be disposed adjacent said bottom, a strip having an intermediate portion thereof positioned between said locking tongues and said bottom, tabs foldably connected to opposite ends of said strip and adapted to be positioned at the

top of said carton between the walls of the carton and the container, said strips being bowed between the top and bottom of the carton and provided with incisions for the reception of pins.
